[57] CLAIM

I claim the ornamental design for a motorcycle saddle seat, as shown and described.

DESCRIPTION

FIG. 1 is a top view of the motorcycle saddle seat. FIG. 2 is a front view of the motorcycle saddle seat. FIG. 3 is a side view of the motorcycle saddle seat. FIG. 4 is a rear view of the motorcycle saddle seat; and, FIG. 5 is a perspective view of the motorcycle saddle seat. The right side view of the motorcycle saddle seat is a mirror image of the left side.
